UNITED STATES PATENT OFFICE.

LLEWELLYN E. JONES, OF SYRACUSE, NEW YORK, ASSIGNOR TO FRAZER & JONES CO., OF SAME PLACE.

HAME-RING.

SPECIFICATION forming part of Letters Patent No. 358,742, dated March 1, 1887.

Application filed December 31, 1886. Serial No. 223,070. (No model.)

To all whom it may concern:

Be it known that I, LLEWELLYN E. JONES, a citizen of the United States, residing at Syracuse, in the county of Onondaga and State 5 of New York, have invented certain new and useful Improvements in Hame-Rings; and I do hereby declare the following to be a full, clear, and exact description of the invention, such as will enable others skilled in the art to 10 which it appertains to make and use the same.

My invention relates to hame-rings; and it consists in the construction and arrangement of the parts of the same, which will be more fully hereinafter described, and pointed out in 15 the claim.

The essential feature of my invention is the formation of a hame-ring having an apertured lug constructed integral with or secured to the outer periphery thereof, forming no inter- 20 nal projection into the body of the ring.

The objects of my invention are to provide hame-rings which are simple and effective in their construction, strong and durable, readily attached to any form of hame, easily understood, cheaply manufactured, and positive in 25 their desired use. I attain these objects by the form of hame-ring illustrated in the accompanying drawings, wherein like letters of reference indicate similar parts in the several 30 views, and in which—

Figure 1 is a side elevation of a portion of a hame with my improved ring shown as attached thereto. Fig. 2 is a plan view of the ring and a portion of the staple on a somewhat enlarged scale. Fig. 3 is a view similar 35 to Fig. 2, showing a modified form of staple. Fig. 4 is a longitudinal vertical section on the line X X of Fig. 2. Fig. 5 is a longitudinal vertical section on the line X X of Fig. 3.

A indicates a hame of an ordinary form of construction having a suitable back iron, a, secured thereto.

C represents the hame-ring, which may be of any preferred form of construction or configuration, and is provided with a lug, C', having an aperture, c', passing therethrough. This lug C' may be formed integral with the ring C, as shown in Figs. 3 and 5, and the aperture

c' cored or drilled through the same; or, as shown in Figs. 2 and 4, a flange may be formed 50 with the ring and thence bent into form around a staple, D, which will have been previously placed therein. The said lug C' may also be formed separate and apart from the ring C, and afterward secured thereto in any suitable 55 manner. The lug C', as illustrated in the drawings, is shown as of cylindrical configuration; but any other form may be used.

When the lug is formed as shown in Figs. 3 and 5, a staple, D, of two sections, may be 50 used, the said parts being inserted in the aperture c', and when secured to the hame A are retained in securement with the said lug in a firm and rigid manner, at the same time allowing of sufficient play of the said ring. 65

The rings when applied with either form of staple are given sufficient play to render them practicable, and are constructed of metal applicable for the purpose, which may be suitably embellished by plating, or other orna- 70 mentation.

The convenience and utility of my improved hame-ring is evident, and need not be enlarged upon here.

It is obvious that slight variations in the 75 construction and arrangement of the parts of my improved ring may be made and substituted for those shown and described without in the least departing from the nature and principle of my invention.

Having thus described my invention, what I claim as new, and desire to secure by Letters Patent, is—

As an improved article of manufacture, a hame-ring having an apertured lug on its external portion formed integral with or secured thereto, and a suitable staple engaging with the apertured portion of said lug and adapted to be secured to the hame, substantially as described. 85

In testimony whereof I affix my signature in presence of two witnesses.

LLEWELLYN E. JONES.

Witnesses:

R. W. JONES,
FRANK CLAYSON.
